CLIP FOR FOUNTAIN PENS AND THE LIKE

Filed April 13, 1926

INVENTOR.
Abraham I. Roller
BY *Alfred H.*

ATTORNEY.

Patented Aug. 31, 1926.

UNITED STATES PATENT OFFICE.

ABRAHAM I. ROLLER, OF BRONX, NEW YORK.

CLIP FOR FOUNTAIN PENS AND THE LIKE.

Application filed April 13, 1926. Serial No. 101,689.

My invention relates to clips for fountain pens, pencils, and the like, and the object of my invention is to produce a clip, which at all times will immovably stay in place on the part of the pen or pencil to which it is attached and will be effectively prevented from gradually working loose and thereby become ineffective as a clip. To this end, I make my clip of two separate parts, a 10 clamping member and a resilient member constituting the clip proper and being rigidly secured to said clamping member. The flexible clamping member being made of U-shape has two prong-like portions, which, 15 when the clip is applied, for instance, to a fountain pen cap, extend through an opening or through slots provided in the wall of said cap into the same and then are bent in opposite directions so as to lie flat against 20 the inner wall of the cap, while the middle portion of the clamping member to which the resilient clip member is secured bears against the outside wall of the cap. A sleeve introduced into the cap covers the bent-over 25 prong portions of the clamp.

For a full understanding of my invention, I refer to the appended drawing, in which I have shown one embodiment of my invention by way of illustration, and in which Fig. 1 shows the clip as seen from the side, while Figs. 2 and 3 show said clip attached to a fountain pen cap, Fig. 3 being a slight modification of Fig. 2.

The clip shown by itself in Fig. 1 consists of a rectangular or U-shaped flexible clamp 1 comprising the prong-like portions 2, 3 and the middle portion 4. To the latter is riveted, or otherwise rigidly secured, at the two places 5 and 6 the resilient clip member 7 which constitutes the clip proper.

When applied to a fountain pen cap, as

shown at 8 in Figs. 2 and 3, the prong-like portions 2, 3 of clamp 1 are passed either through a common opening or recess 9 in the wall of cap 8 (see Fig. 2), or they are 45 passed through separate slots 10, 11 provided in the wall of cap 8. Thereupon the inwardly projecting ends of the flexible prong-like portions 2, 3 are bent over in opposite directions so as to lie flat against the 50 inner wall of the cap, whereby the entire clip is securely held in place. For greater security, an inner sleeve 12 of suitable material is introduced into the cap exactly fitting the same, as shown in Figs. 2 and 3, and thereby any tendency of the bent-over prong-like portions 2, 3 of clamp 1 to pull out or become dislodged, is effectively prevented. As the resilient clip-member 7 is 55 rigidly secured to the middle portion 4 of clamp 1, being riveted thereto at two places, the clip-member 7 will thus be immovably retained in position effectively resisting any strains adapted to loosen the clip-member and thereby destroy its function.

While I have described and shown my new clip in great detail, I do not, of course, limit myself to the exact construction as herein disclosed, but claim as my invention:

In combination with the cap of a pen having spaced openings in its wall, a clip comprising a U-shaped flexible clamp, projections upon said clamp adapted to extend through said openings into said cap and to be bent against the inner wall thereof, a resilient member riveted to the central portion of said clamp by two spaced rivets so that the desired flexibility is secured throughout the clamp and resilient member.

In testimony whereof I affix my signature.

ABRAHAM I. ROLLER.
